Primary Examiner — Brett Miller*Assistant Examiner* — Jasmine L. Comedy(74) *Attorney, Agent, or Firm* — Standley Law Group LLP; Adam J. Smith; Jeffrey S. Standley(57) **CLAIM**

The ornamental design for an outdoor fitness pavilion, as shown and described.

DESCRIPTION

FIG. 1 is a top perspective view of the outdoor fitness pavilion;

FIG. 2 is a bottom perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof;

FIG. 8 is a bottom plan view thereof; and,

FIG. 9 is a bottom perspective view thereof with certain unclaimed features illustrated in broken line.

The broken lines form no part of the claimed design.
